UNITED STATES PATENT OFFICE

2,067,496

INTERNAL COMBUSTION ENGINE

John J. McCarthy, Malden, Mass.

Application June 4, 1932, Serial No. 615,376

10 Claims. (Cl. 123—50)

My present invention relates to internal combustion engines of the type wherein each cylinder has two concentric pistons, the outer piston being in the form of a sleeve in which the inner piston reciprocates, and both being arranged to reciprocate in time relation and in opposite directions, my present invention being an improvement of my prior United States Letters Patents Nos. 1,823,500, dated September 15, 1931, and 1,903,511, dated April 11, 1933.

Important objects of my present invention are to improve and perfect engines of the double-opposed piston type, to render them free of vibration, and provide substantially perfect balanced construction and operation; to have means which will quickly, completely, and automatically clean out and scavenge the consumed gases from the cylinders through the action of the reciprocating pistons; to insure the correct lubrication of the double-opposed pistons by positively drawing oil vapor from the crank case to the top of the cylinder, and to improve and perfect engines of the double-opposed cylinder type.

Preferably my invention is embodied in an engine of the Diesel or compression ignition type, and operating on the two-stroke cycle principle, which latter is peculiarly advantageous in a double-opposed piston type, wherein an engine of given power will be compact, have fewer parts, and requires only about one-half the number of cylinders to produce the same power as double the cylinders in a four-stroke cycle engine.

My novel method of scavenging the cylinders is positive and most important; and for relatively high-powered units a rotary blower would be utilized for this purpose, although a single air-pump piston would be suitable for small lower-powered units.

An important feature is the arrangement of a circular manifold permitting the intake air to enter in a tangential manner, thus inducing swirling currents of air in the working cylinders between the pistons, which air furnishes the highly desired turbulence for Diesel operation.

In the drawings, illustrating a preferred embodiment of the invention, a two-cylinder engine operating on the Diesel or compression ignition cycle is shown.

Fig. 1 is a longitudinal sectional view. The left-hand cylinder shall be designated as cylinder #1 hereafter, likewise cylinder #2 is the right-hand cylinder.

Fig. 2 is a longitudinal elevation.

Fig. 3 is a transverse section showing the pis-

ton #1 part way down and the sleeve #2 partly up on their respective power strokes.

Fig. 4 shows a modification of Fig. 3. Fig. 4 contains the enlarged scavenge pump piston #28 with a transfer valve #26 as predominant feature.

Fig. 5 is likewise another modification of Fig. 3. Fig. 5 embodies an enlarged single-acting pump piston #39 attached to sleeve #2.

Fig. 6 is part of transverse view with precombustion chamber #41 external to working cylinder.

Figs. 7 and 8 are horizontal sections through intake and exhaust ports respectively.

Referring now to Fig. 1 for a specific description of the construction features embodied in my invention, 1 is the working piston with piston rings 11, and linked to the crankshaft 7 by a connecting rod 6. The piston pin 12 has suitable plugs 13 made of soft alloy to prevent piston pin 20 from scoring sleeve 2. Said piston 1 reciprocates within sleeve 2. At the bottom of said sleeve 2 are two bosses 4 diametrically opposite and the axes of said bosses 4 are parallel to center line of crankshaft 7.

Two short connecting rods 5 of equal length connect said working sleeve to crankshaft. The crankthrow for rod 6 is nearly opposite that for the short rods 5. The crankshaft 7 is mounted on main bearings 10, the latter are supported by 30 crankcases 8 and 9. Onto crankcase 8 is mounted a cylinder block 18. Said working sleeve reciprocates in cylinder block 18. In the cylinder block and said sleeve are intake and exhaust ports 14 and 16, respectively. Similarly 35 15 and 17 are intake and exhaust manifolds respectively. The water jacket is 19. Attached to the upper end of the sleeve is a head 3. In cylinder 1 the piston is at the bottom dead center and the sleeve is near or at top dead center 40 revealing the working cylinder 20. In the combustion chamber 20 (in cylinder No. 2) is an end view of injection nozzle 24. The top cover 21 serves only as a case and communicates to the 45 crankcase by breather passage 25.

In Fig. 2 the intake and exhaust pipes 22 and 23 respectively are the only parts not shown in Fig. 1. The intake pipe 22 is connected to a rotary blower which is not shown on these drawings. The injection nozzles 24 are here indicated 50 more clearly than in Fig. 1.

Fig. 3 shows the relative positions of the crankthrows on the crankshaft 7. In this case the included angle between said crankthrows is 170°. In other words, if the rotation is clock- 55

wise, the crankthrow for the piston leads that for the sleeve by 10°. All parts in this figure are numbered the same as in Fig. 1. The injection nozzles are clearly shown. Note section A—A, reference to which will be made in Figs. 4 and 5.

5 A modification of Fig. 3 above section A—A is shown in Fig. 4 with respect to the scavenging compressor and transfer of the charge. 28 is a head on sleeve 2 as well as being a pump piston 10 in pump cylinder 31. The intake passages 34 surround the cage supporting inlet check valves 32. The latter are mounted in pump cylinder head 33. A piston ring 30 is used on pump piston 28. In a valve guide 29 secured in pump 15 piston 28 slides a transfer valve 26. Said transfer valve seats upon valve seat 27, the latter being secured to pump piston 28. There are not intake ports in this arrangement but transfer of compressed charge takes place past the check 20 valve 26.

In Fig. 5, 34 indicates inlet passages, 32 are inlet check valves, 31 is a pump cylinder, 38 are outlet check valves connecting into passages 36 and thence to ports in cylinder block 18 and 25 corresponding ports 14 in sleeve 2. The pump piston 39 also forms head on sleeve 2 and is rigidly attached thereon and reciprocates with said 30 sleeve 2. Space 40 is connected by breather pipes to crankcase.

30 Fig. 6 is similar to Fig. 3 except that combustion occurs in precombustion chamber 41 instead of in working cylinder 20. 44 is an orifice connecting said precombustion chamber 41 with cylinder 20. This precombustion chamber 41 is 35 spherical in shape and injection nozzle 24 is screwed into said chamber. A glow plug 43 to furnish heat from an electric current through wire 45 for starting ease in cold weather is illustrated.

40 Fig. 7 and Fig. 8 are sections through intake and exhaust ports respectively, where said ports are open, as is shown in cylinder No. 1 of Fig. 1. The manifold 15 extends around the cylinder and is an integral part of cylinder block 18 in 45 Fig. 1. Ports 14 are arranged so as to enable air to flow into cylinder 20 from all sides. The center line of said ports 14 is so placed as to produce a tangential flow into cylinder 20. On the other hand, the exhaust ports 16 in Fig. 8 are 50 arranged to conduct the rotation of exhaust gases out with the least amount of resistance into manifold 17.

The operation of my engine is very simple and will be readily understood by those skilled in this 55 art, being described as follows.

If we assume that the engine is a two-cylinder engine, constructed as described above and as illustrated in the drawings, such operation will be as follows:

60 The motor will be rotated by a crank or conventional starter. Referring to Fig. 1, air will be furnished under pressure from a scavenging pump or blower driven from the engine, to cylinder No. 1 through intake pipe 22 (Fig. 2), manifold 15, and ports 14, thence into cylinder 20. As crankshaft 7 rotates the piston 1 travels upward and the sleeve 2 moves downward until the air in cylinder 20 is compressed to a high temperature and pressure.

70 The component parts will then appear as in cylinder No. 2. At or near this dead center position, ports 14 in sleeve 2 uncover injection nozzle 24 and fuel is injected into combustion chamber 20 and combustion takes place. The injected fuel is properly timed by an injection

5 pump operated from the timing mechanism of the engine. As the combustion progresses the pressure will rise further and force the piston 1 downward and the force on the sleeve head will drive the sleeve upward. Fig. 3, the transverse section, shows the charge in working cylinder 20 on the expansion stroke. The power is then transmitted through connecting rods 5 and 6 to crankshaft 7. Connecting rod 6 exerting a push on the crankshaft 7 and connecting rods 5 10 exert a pull. When the piston 1 nears the bottom of its travel and vice versa for sleeve 2, the exhaust ports 16 are uncovered and the pressure falls in cylinder 20. At a short timed interval later the intake ports 14 are uncovered and the 15 charge of air flows in through ports 14 and forces the residual products of combustion to be scavenged from cylinder 20 through exhaust ports 16. This operation takes place all in one revolution of the crankshaft 7 and the component parts are now in a position as shown in cylinder No. 1 of Fig. 1, ready for the above described cycle to be repeated.

20 During the operation of the engine there will be changes in the volume and pressure under 25 case 21 and this compartment is connected by passage 25 to enable oil vapor to be drawn up and lubricate the upper end of cylinder in which the sleeve 2 and head 3 operate.

In Fig. 4 the single acting pump piston is on 30 the downward or intake stroke. The air flows through passages 34 and past the check valve 32 into pump cylinder 31. When the pump piston 28 reaches the bottom of its stroke, a full 35 charge of air will have been taken in and the automatic valves 32 will close. On the return stroke valve 26 will be opened automatically by the pressure built up in cylinder 31 and the compressed air will flow from the pump cylinder into cylinder 20, thus filling said cylinder 20 with a 40 fresh charge of air and also scavenging from it the residual products. Shortly after the pump piston 28 reaches top dead center the transfer valve 26 closes automatically and the charge of air just introduced into cylinder 20 is ready for the 45 compression stroke when sleeve 2 moves downward again. The piston ring 30 on the pump piston 28 seals said pump piston in cylinder 31. The space in cylinder 31 beneath the enlarged 50 part of pump piston 28 is connected to the crank case so that oil vapor may be circulated in said space and lubricate the upper part of the cylinder in which the sleeve 2 reciprocates.

Similar to Fig. 4 is Fig. 5 which contains a 55 single acting pump piston 39 without a transfer valve as a combined feature. Said pump piston 39 is on the intake or suction stroke. The air is induced to flow from the outside through passages 34 and past the automatic valves 32 into cylinder 31 until said pump piston 39 has approximately reached the bottom dead center position. At this time the inlet check valves 32 close and the sleeve 2 along with the pump piston 39 returns upwards and compresses the air in cylinder 31 until the automatic outlet check 60 valves 38 open.

The compressed charge of air then flows into passage 36 and when the sleeve 2 along with pump piston 39 nears its uppermost position, the intake ports into cylinder 20 are uncovered and 70 the charge of air flows into said working cylinder 20. Scavenging of the residual products of combustion and a fresh charge of air is obtained in working cylinder 20. Said outlet valves 38 close when the pump piston 39 again starts downward.

Heretofore, the combustion has been described as taking place in the working cylinder 20. In Fig. 6 the operation is the same as described for Figs. 1 and 3, except that on the compression stroke the air is forced into a precombustion chamber 41 through an orifice 44 so as to produce a high rate of turbulence or rotation in said chamber 41. At or near the top dead center of piston 1 and likewise near bottom dead center of the sleeve 2 with head 3, fuel is injected at the properly timed interval through nozzle 24 into the whirling air in chamber 41, which is at a high temperature, due to compression. Combustion then takes place in said precombustion chamber 41 and the pressure and temperature of the charge rise and the charge escapes through orifice 44 into the working cylinder 20. Piston 1 is then forced downward and the pressure on head 3 drives the sleeve upward similar to the operation for Fig. 1 and Fig. 3. When the motor is very cold at starting, the glow plug 43 can be put into action by passing an electric current through the coil of wire 42 and thus heating said coil so that when the injected fuel and air pass rapidly over this hot wire, combustion will take place more readily by raising the temperature of the charge.

In Fig. 7 the intake air flows into the circular manifold 15 and flows around it in a rotating manner. At properly timed intervals the sleeve 2 with ports to match those in cylinder block 18 uncovers said ports 14 and permits the charge of air to flow into working cylinder 20 in a tangential manner. This induces an orderly rotation of the air in the working cylinder 20 which furnishes the required turbulence for Diesel operation.

Fig. 8, section through exhaust ports, operates in the reverse manner to that of intake of the charge shown in Fig. 7.

I claim:

1. An internal combustion engine of the kind described having a cylinder containing a pair of concentrically mounted opposed pistons arranged to move in opposite directions with respect to each other, one of said pistons being in the form of a sleeve, and the other piston operating within said sleeve in timed relation and in the opposite direction, said sleeve carrying an air pump at the end opposite the engine crank shaft, transfer passages leading from said pump to said cylinders, and means associated with said passages effecting a tangential air delivery into the working chamber between said pistons operating at properly timed intervals based upon ports in said working sleeve uncovering ports in said cylinder.

2. An internal combustion engine of the kind described operating on the two-stroke cycle and compression ignition principle, having a plurality of cylinders, each cylinder containing a pair of concentrically mounted opposed pistons arranged to move in timed relation and in opposite directions respectively, one of each of said pistons being in the form of a sleeve, and the companion piston operating within said sleeve, each sleeve carrying an air pump at the end opposite the engine crank shaft, transfer passages leading from said pump to said cylinders, said passages terminating in ports tangentially arranged with respect to said cylinders to effect a tangential air delivery into the working chambers between said pistons operating at properly timed intervals based upon ports in said working sleeve uncovering ports in said cylinder.

3. An internal combustion engine having opposed reciprocating pistons in the cylinder, one of said pistons having a sleeve and the other piston operating within said sleeve in timed relation and in the opposite direction, a passage 5 from the crank case to the upper part of the engine, a manifold adjacent said cylinder, tangentially arranged ports associated with said manifold, ports in said sleeve piston adapted to cooperate with said manifold ports to scavenge 10 said cylinder on the exhaust stroke, said sleeve piston operating on the compression stroke to feed oil vapor from the crankcase to the upper port of the engine.

4. An internal combustion engine operating on 15 the two-cycle and compression ignition principles, having a plurality of sets of opposed reciprocating pistons in each cylinder, one of each of said pistons having an outer sleeve in contact with the cylinder walls, and with the inner part 20 of said sleeve constituting the walls for the opposed piston operating within said sleeve, means supplying air under pressure around said cylinder, ports in the cylinder cooperating with a plurality of sets of ports in each sleeve of the 25 outer piston of a pair, providing tangential injection of scavenging air at proper intervals between said pistons, in combination with means automatically actuated by the reciprocation of one of said pistons to insure the oiling of the 30 upper part of said cylinder and sleeve.

5. An internal combustion engine operating on the two-cycle and compression ignition principles, having a cylinder with two pistons operating in opposite directions, one piston comprising a sleeve in which the oppositely moving piston operates, said sleeve having a set of intake ports near the upper end, and a set of exhaust ports near the lower end, a manifold adjacent said cylinder, cylinder intake ports as 40 associated with said manifold and arranged to cooperate with said sleeve intake ports to provide a tangential air intake for scavenging the burnt gases on the exhaust stroke.

6. An internal combustion engine operating 45 on the two-cycle and compression ignition principles, having a plurality of sets of opposed reciprocating pistons in each cylinder, one of each of said pistons having an outer sleeve in contact with the cylinder walls, and with the inner 50 part of said sleeve constituting the walls for the opposed piston operating within said sleeve, means supplying air under pressure around said cylinder, ports in the cylinder cooperating with a plurality of sets of ports in each sleeve of the 55 outer piston of a pair, providing tangential injection of scavenging air at proper intervals between said pistons based upon ports in the working sleeve uncovering ports in the cylinder.

7. An internal combustion engine of the character described operating on the two-cycle and compression ignition principles, having a cylinder with two pistons operating in opposite directions and forming a working chamber, one of said pistons comprising a sleeve, intake ports 65 to said working chamber, and conducting means to feed air to said ports, said ports being arranged to provide a tangential air intake into said working chamber.

8. An internal combustion engine of the character described operating on the two-cycle and compression ignition principles, having a cylinder with two pistons operating in opposite directions and forming a working chamber, cylinder intake ports, one piston comprising a sleeve, 75

- said sleeve having ports adapted to register with said cylinder ports, said cylinder ports being tangentially arranged with respect to said cylinder to direct air in a tangential flow into said working chamber.
9. An internal combustion engine of the character described having opposed reciprocating pistons in each cylinder forming a working chamber, one of said pistons comprising a sleeve, intake ports to said working chamber tangentially arranged with respect to said cylinder, exhaust ports from said working chamber tangentially arranged with respect to said cylinder, said intake ports and said exhaust ports cooperating to direct air in a tangential flow through said working chamber to produce a tangential scavenging of burnt gases on the

exhaust stroke, said intake ports providing a tangential air flow into said working chamber to provide turbulence on the compression stroke.

10. An internal combustion engine of the character described having opposed reciprocating pistons in each cylinder forming a working chamber, intake ports to said working chamber, conducting means to feed air to said ports, said means and said ports cooperating to provide a tangential air intake into said working chamber and exhaust ports tangentially arranged with respect to said cylinder to cooperate with said tangential intake to provide a tangential scavenging of burnt gases from said working chamber.

JOHN J. McCARTHY.
